UNITED STATES PATENT OFFICE.

EDWARD A. HINE, OF NEWARK, NEW JERSEY.

LOCK FOR DOOR-KNOBS.

No. 868,925.

Specification of Letters Patent.

Patented Oct. 22, 1907.

Application filed May 3, 1907. Serial No. 371,730.

To all whom it may concern:

Be it known that I, EDWARD A. HINE, a citizen of the United States, residing at 209 Washington avenue, Newark, county of Essex, and State of New Jersey, have invented certain new and useful Improvements 5 in Locks for Door-Knobs, fully described and represented in the following specification and the accompanying drawings, forming a part of the same.

The object of this invention is to prevent the theft 10 of metallic doorknobs, which have often been stolen to be sold as junk metal, because they can be detached by merely removing the knob-screw which holds the knob on the spindle.

The improvement consists of a latch or pawl jointed 15 upon the spindle in a suitable position to engage a shoulder within the knob-shank or knob, in addition to the ordinary or usual fastening for the knob.

Where only one side of the door is exposed, as in 20 locked vestibule doors, the inner end of the spindle may have the knob secured by a knob-screw, and the outer knob secured by the pawl, so that from the outer end of the spindle the knob cannot be removed.

Where both sides of the door are exposed, the two 25 knobs can be protected from theft by forming the "rose" upon one side of the door deep enough to cover the knob-screw and securing one knob by such screw, the other knob being secured by the pawl, as already described.

By pivoting the pawl in a slot in the knob-spindle, 30 the pawl is adapted to slide through the hole in the lock and in the knob-shank, but is then moved by gravity out of the slot to engage the shoulder in the knob; and where the knob-screw for the opposite knob is inclosed in the "rose," neither knob can be removed 35 without taking the door from its hinges and laying it horizontally, so that the vertical position then assumed by the spindle may permit the pawl to fall into line with the spindle, which enables the knob to be withdrawn.

40 The invention will be understood by reference to the annexed drawing, in which

Figure 1 is an edge view of a door with the spindle and two knobs, one of such knobs and "rose" being shown in section. Fig. 2 is a plan of a spindle with 45 one end expansible and the opposite end provided with a gravity pawl, and Fig. 3 is a cross section of the knob-shank and spindle at the expansible end of the spindle. Fig. 4 is a section of the doorknob with the end of the spindle therein showing an alternative construction.

50 *a* designates the door, *b* the face-plate of the door-lock, and *c* the spindle extending through the same.

d is a "rose" upon one side of the door with the shank *e* of the knob *A* secured upon the end of the 55 spindle by a knob-screw *f*, and the socket in the "rose"

f of sufficient depth to cover such knob-screw, and thus prevent the releasing of the knob from the spindle.

The head of the screw *f* is represented by dotted lines in Fig. 1 to illustrate its concealment by the socket of the "rose", and the screw may be threaded 60 into a hole in the spindle, as represented for the knob-screw *k* at the opposite end of the spindle. At the opposite end within the knob *B* the spindle is provided with a pawl *g* pivoted by a pin *h* in a slot *i* extended into the end of the spindle, in addition to a 65 knob-screw *k*.

The end of the pawl is shown projected toward the opposite end of the spindle, and is so weighted or proportioned that when the spindle is placed with the slot *i* in a vertical or approximately vertical position, the 70 weight of the pawl will carry its point downward and out of the slot.

The knobs are thus secured to the spindle by the concealed knob-screw *f* at one end and the exposed knob-screw *k* at the other end; while the pawl furnishes 75 an additional means for positively preventing the removal of the knob *B* from the spindle.

By suitably proportioning the length of the spindle to the thickness of the door and the length of the knob-shank, such dropping of the pawl may be adapted to 80 engage its inner end with a shoulder *j* upon the inner end of the shank to permanently hold the knob from removal, as the knob-spindle does not in practice rotate far enough to turn the pawl up-side-down and thus release it from the shoulder *j*. 85

In practice, knobs do not turn more than 90 degrees, and are commonly made to turn each way from their normal position so as to retract the latch whether turned to the right or left. The ordinary movement each side of the normal position is commonly less than 45 degrees 90 so that the pawl when applied to ordinary knobs permanently locks the knob to the spindle so long as the spindle remained in its operative position, which is horizontal.

The pawl is adapted to be used independently of the 95 ordinary fastenings for the knobs, to merely prevent the removal of the knob from the spindle, as the ordinary knob-screws and other attachments may be used to secure the knobs upon a spindle in their operative relation to the door, and the pawl may be used as a reserve 100 or additional attachment to absolutely prevent the removal of the knob if such ordinary fastenings are loosened.

The knob-screw *k* upon the shank of the knob *B*, is 105 adapted to secure the knob in its working position, so that the pawl is not required to hold the knob in its operative relation to the spindle or the door. It is, therefore, immaterial whether the end of the pawl is in contact with the shoulder during the normal operation of the doorknob, as the pawl operates when the 110

other fastening is loosened to contact with the shoulder and prevent the removal of the knob. This is illustrated in Fig. 4, where a pawl *g* is shown with arms arranged to project at both sides of the spindle but 5 weighted at one end so that it normally falls across the spindle when pushed into the recess of the knob. With such construction, the spindle must be forced into the knob about one-eighth of an inch farther than is necessary to make the pawl contact with the shoulder 10 to enable the pawl to turn transversely to the spindle; but the knob-screw *k* serves to hold the knob in its working position, leaving the pawl at a distance from the shoulder as shown in Fig. 4, to operate merely as a lock if the knob-screw be loosened and an attempt be 15 made to remove the knob. The pawl does not, therefore, need to form any working part of the device when the knob is in operation, as the ordinary fastenings for the knob serve such purpose, but comes into play when an attempt is made to remove the knob, when it 20 contacts with the shoulder and prevents such removal. This is further illustrated in Figs. 2 and 3, where one end of the spindle is shown with a beveled slot *l* in its end and a wedge *m* fitted therein to be pressed by the knob-screw *n*, for the purpose of expanding 25 the spindle to clamp it at any point within the shank *e* of the knob. This is the ordinary form of expansible spindle for adjusting the knobs accurately into their working position upon opposite sides of the door, and affords a means of adjusting the knob upon 30 one end when the knob at the other end is provided with the pawl *g*, which is not constructed or intended in my invention to furnish a means of securing the knob in different positions upon the spindle, but to positively prevent its abstraction. The screw *n* for 35 operating with such a spindle can be concealed in a deep "rose" *f* and the knob thus be protected from theft the same as the screw *f* shown in Fig. 1.

A hollow metallic knob is shown in the drawing; but it is obvious that the invention is applicable to any 40 knob, as of wood or other material, if a recess of sufficient depth be made within the same to receive the inner end of the spindle and the pawl.

Having thus set forth the nature of the invention what is claimed herein is:

1. A knob spindle having a knob fitted removably thereon, means to hold the knob in an adjusted position on the spindle, and a pawl upon the spindle constructed and arranged to fit within the knob and permanently lock the same to the spindle while in its operative horizontal position. 45

2. A knob spindle having a knob fitted removably thereon means to hold the knob in an adjusted position on the spindle, and a pawl pivoted upon the spindle and movable by gravity and constructed and arranged to engage and retain engagement with the knob to prevent the removal 55 of the knob while the spindle is in its operative horizontal position, and arranged and operated to release the knob by the gravity movement of the pawl when the spindle is turned to a vertical position. 50

3. The combination, with a knob spindle having upon one end a knob with a shank and a knob-screw adapted to secure the knob at any point upon the spindle to adjust it to the door, of a "rose" adapted to cover said knob-screw to prevent the abstraction of the knob, the opposite end of the spindle having a knob with an internal shoulder, and such opposite end of the spindle having a pawl constructed and arranged to fall by gravity into engagement with the shoulder in the knob to positively prevent the removal of such knob while the spindle is in its operative horizontal position. 60

4. A door provided with a lock having a knob-spindle, a recessed knob having a shank fitted upon the spindle and provided with a shoulder at the inner end of the shank, said spindle having a pawl adapted to pass through the hole in the knob-shank and movable by gravity into 75 contact with the shoulder upon the shank to prevent the removal of the knob while the door is in an operative position, the construction permitting the pawl to fall into line with the spindle to withdraw the knob when the door is unhinged and turned into a different position and means 80 to hold the knob in an adjusted position on the spindle. 70

5. The combination, with a knob-spindle having door-knobs upon opposite ends and means for separately securing them in their working relation to the door, of an additional means applied to the spindle within at least 85 one of the knobs for positively preventing its removal from the spindle.

In testimony whereof I have hereunto set my hand in the presence of two subscribing witnesses.

EDWARD A. HINE.
